UNITED STATES PATENT OFFICE.

ALLEN G. WOOD, OF UTICA, NEW YORK.

TAIL-PIECE FOR BANJOS OR VIOLINS.

SPECIFICATION forming part of Letters Patent No. 360,790, dated April 5, 1887.

Application filed August 5, 1886. Serial No. 210,106. (No model.)

To all whom it may concern:

Be it known that I, ALLEN G. WOOD, a citizen of the United States, residing at Utica, in the county of Oneida, State of New York, have 5 invented certain new and useful Improvements in Tail-Pieces for Banjos, Violins, &c., of which the following is a specification, reference being therein to the accompanying drawings.

My invention relates to improvements in 10 "tail-pieces" for banjos, guitars, violins, and other stringed instruments of like character.

The object of my invention is to provide a 15 convenient, cheap, and reliable tail-piece for holding the strings of banjos, violins, &c., which will not cut or injure the strings.

My invention consists of a tail-piece for 20 stringed instruments, having suitable fastening devices, to which the rear ends of the strings are looped or wound, and a series of retaining devices around which the strings are passed, whereby the strain of the strings is distributed between the fastening and retaining devices, as will more fully hereinafter appear.

25 Referring to the drawings, Figure 1 is a view in perspective of a banjo with my improved tail-piece secured thereto. Fig. 2 is a view in perspective of the tail-piece detached from the instrument. Fig. 3 is a modification.

30 A indicates a banjo or other instrument of like character provided with the usual number of strings and the ordinary tension devices, B, for regulating the pitch or tone of the strings.

35 C is the tail-piece, secured to the rear end of the instrument by means of the open link D and pin E, or in any other convenient manner. The plate C, forming the tail-piece, is made of metal or other suitable material, and is provided with one or more headed standards or buttons, F, near its rear end, to which the rear ends of the strings a are looped, tied, or wrapped in a suitable manner. The front end of the plate C is provided with a series of but-

40 tons or headed pins, G, around which each string is wrapped once and then led forward and secured to the tension devices B, by which

the strings are drawn up to tune the instrument.

The headed standard or pin F serves to hold 50 the rear ends of all the strings, as already indicated, (or a series of these standards may be arranged near the rear end of the plate,) while the headed pins or buttons G serve to relieve or take a portion of the strain from off the 55 standard and the extreme ends of the strings and at the same time admit of a flexible or yielding support between the tension devices and the main standard F, and also serve to keep the strings at a uniform distance apart. 60

In Fig. 3 I have shown a modification of my invention, and in this instance a perforated rib, H, is formed on the plate, through which the rear end of the strings are passed and tied or knotted, while the front end of the plate 65 is provided with a series of perforations, I, through which the strings are passed, as shown, and wrapped around the front end of the plate. By this arrangement should a string break another can be quickly put on, while at the same 70 time there is nothing connected with the tail-piece which will in any way cut the strings and cause them to break at this end, as is the case with the tail-pieces now in general use.

Having thus described my invention, what 75 I claim, and desire to secure by Letters Patent, is—

1. A tail-piece for banjos, violins, &c., consisting of a plate provided with a standard or button near its rear end, to which the strings 80 are secured, and a series of buttons or headed studs near its front end, around which the strings are passed, as set forth.

2. In a tail-piece for banjos, violins, &c., the plate C, provided with the standard F and 85 buttons G, in combination with the strings a, and tension devices B, as set forth.

In testimony whereof I affix my signature in presence of two witnesses.

ALLEN G. WOOD.
